UNITED STATES PATENT OFFICE

2,479,604

WARP TYING MACHINE

Charles B. Crandall, Rockford, Ill., assignor to
 Barber-Colman Company, Rockford, Ill., a corporation of Illinois

Application January 2, 1948, Serial No. 109

11 Claims. (Cl. 28—49)

1

The invention pertains to warp tying machines of the type disclosed in Colman Patent No. 1,442,776 and Noling Patent No. 2,188,394, and has particular reference to the provision in a warp tying machine of means for facilitating the "loading" of the old and new warps in the machine preparatory to tying.

Warp tying machines of the character referred to are equipped with two pairs of warp clamps, one pair for the old warp and one pair for the new, with the corresponding clamps of each pair disposed in vertically spaced relation so as to hold the two sheets of warp threads during the tying operation. As set forth in said Colman patent, each of the clamps includes an outwardly opening U-shaped clamping member adapted for the reception of an insertion bar to grip and hold warp threads. Such insertion bars have heretofore commonly been placed in their respective clamps by hand. This has not only entailed loss of time but some difficulty particularly in the case of machines designed to operate upon wide warps on the order of fifty-six inches in width due to the difficulty of handling long insertion bars which are of necessity made thin and somewhat flexible.

With the foregoing in view, the object of the present invention, generally stated, is to provide in a warp tying machine insertion bar carriers arranged for easy manipulation in the operation of inserting the bars into their respective clamps.

A further object is to provide insertion bar carriers for use in combination with an auxiliary holder for the thread ends, which holder is mounted on the warp tying machine for movement into either of two positions spaced apart vertically in accordance with the spacing of the two pairs of warp clamps.

The objects of the invention thus generally set forth, together with other and ancillary advantages, are attained by the construction and arrangement shown by way of illustration in the accompanying drawings, in which:

Figure 1 is a front elevational view of a warp tying machine embodying my invention.

Fig. 2 is a fragmentary end elevational view of the improved warp tying machine in loading position with respect to a loom of which only the pertinent portions are shown schematically.

Fig. 3 is a horizontal section taken approximately in the plane of line 3—3 of Fig. 1.

Fig. 4 is a fragmentary vertical sectional view through the machine and illustrating the loading of the new warp into the machine.

2

Fig. 5 is a fragmentary detail view of a locking device for the auxiliary thread holder.

Fig. 6 is a fragmentary sectional view showing the mounting of the clamping means of the auxiliary thread holder for endwise adjustment.

Fig. 7 is a view similar to Fig. 4 but illustrating the loading of the old warp.

My invention is herein disclosed as embodied in a portable machine especially adapted to be placed behind a loom requiring warp replenishment. That part of the machine which is toward the loom will be referred to as the loom side, and the opposite side as the front side.

The machine comprises a supporting framework 10 having a bed 11 provided with a gib 12 along which the carriage of the warp uniting mechanism is arranged to travel. The carriage is not herein shown but its over-all dimensions are indicated in dotted outline at 13 in Fig. 2.

Portions of the two warps to be united are supported in the path of the warp uniting mechanism. The supports for the new warps comprise a pair of clamps 14 and 15 and the supports for the old warp comprise a pair of clamps 16 and 17. Each clamp comprises an outwardly opening U-shaped member 18 equipped with toothed clamping bars 18a (Fig. 1) providing cam surfaces for coaction upon relative longitudinal movement of the bars to grip an insertion bar together with the warp threads, suitable means such as levers 18b being provided for shifting one of the bars. Herein shown are four insertion bars 14a, 15a, 16a, 17a, one for each of the clamps.

The clamps 16 and 17 are mounted upon a warp carriage generally designated 19, pivotally supported on the machine frame in the manner disclosed in said Noling patent. On the loom side of the machine the two warps are additionally supported by two ribbon bars 20 and 20a, one for the upper or old warp and the other for the lower or new warp.

On the front side of the machine is mounted a support 21 for an auxiliary holder for the thread ends, herein shown in the form of a conventional plush clamp 22, the members of which are yieldably clamped together by means of spring clips 22a. The support 21 comprises, as shown, a pair of arms 23 connected by a tie rod 23a and mounted on a rockshaft 24. The latter forms a part of a vertically slidable rectangular frame 25 (Fig. 1) having end members 26 and a lower cross rod 26a.

The frame 25 is guided for up and down movement on the machine by means of rollers 27 coacting with upright tracks 28 fixed on the front side of the machine. The arm 23 is adapted to be

3

locked to the shaft so as to hold it closely adjacent the side of the machine as shown in broken lines in Fig. 4 through the medium of a screw clamp 29 (Fig. 5). Outward movement of the clamp support 21 is limited by extensions 30 on the lower arms 23 arranged for engagement with the tracks 28.

The frame 25 has a lower or inactive position and when in this position the clamp support 21 is held against the frame. For this purpose, the lower ends 30 of the arms 23 coact with stationary cam members 31. The support also is adapted to be latched in either of two active positions in one of which the plush clamp 22 is positioned for supporting the ends of the old warp and in the other of which it is positioned for clamping the ends of the new warp. The means for holding the support in either of these two active positions comprises as shown a latch 32 journaled on the shaft 24 and arranged for coaction with slots 33 and 34 in an upright plate 35 disposed midway between the ends of the frame as shown in Fig. 1. Rigid with the latch 32 is a fingerpiece 36 carrying a spring pressed plunger 37 bearing upon a stationary cross bar 38 suitably supported by the shaft 24. The latch member 32 is thus yieldably urged in the direction of the plate 35 so as to enter the slots 33 and 34 therein. The slots 33 and 34 are so positioned that when the latch member engages with the lower slot the plush clamp 22 will occupy the proper position with respect to the new warp, and when it engages with the slot 34 will occupy the proper position with respect to the old warp.

The plush clamp is mounted for endwise adjustment on the upper end of the support 21. As shown in Fig. 6, the lower member is yieldably secured to the support by means of bolts 38a having flat heads 38b engaging on T-slots 38c, the latter being formed in a plate 38d rigid with the lower clamping member.

In accordance with my invention, I provide a pair of insertion bar carriers 39 and 40 swingably mounted on the machine frame on rock-shafts 41 and 41a at the loom and front sides thereof respectively and operative to support the respective insertion bars for movement into their respective clamps. Each of the carriers comprises, as shown, a pair of arms 42 and 43 and an intermediate arm 44 disposed substantially midway between arms 42 and 43 and made relatively thin so as to be capable of passage through the warps without injury thereto. The arms 42, 43 and 44 are fast upon the respective shafts 41 and 41a and each is provided with longitudinally spaced notches 45 and 46 for the reception respectively of the insertion bars 14a and 16a, or 15a and 17a, as the case may be. The arms 42 and 43 are further provided with ball detents 47 for yieldably retaining the insertion bars in their respective notches.

Inasmuch as the carrier 39 is mounted on the loom side of the machine and therefore not conveniently accessible, a treadle operated means is provided for swinging the carrier. This means comprises a short arm 50 connected by a link 51 to a bell crank 52 which in turn is connected by a link 53 with a treadle 54 mounted on the base of the machine and projecting forwardly therefrom. A spring 54a, only a portion of which is shown in dotted lines in Fig. 2, serves to return the carrier 39 when the treadle is released. The carrier 40 being located at the front side of the machine, is provided with a handle 55 on the arm 43. Additionally, this carrier has rigid therewith a notched collar 56a for coaction with

5 a latch 54b to hold the carrier in spaced relation to the clamp 15 as shown in full lines in Fig. 4.

6 The operation of loading the two warps into the loading machine will now be described, having special reference to Figs. 2, 4 and 7.

7 The old warp beam W having approached the point of exhaustion, the warp is clamped adjacent the beam by means of a clamp A, then severed from the beam and the clamp placed upon the loom in the position a (Fig. 2). The beam W is then replaced by the new beam W', the warp clamped close to the beam by means of a clamp B, drawn forwardly to provide a length L and then again clamped adjacent the beam by means of a clamp C. The length L is then wrapped around the clamp B and both of the clamps B and C placed upon the loom in the positions designated respectively as b and c, a sufficient length of yarn being drawn off from the beam W' to permit passage around the whip roll R of the loom.

8 The warp tying machine is now moved into position closely adjacent the loom, as shown in Fig. 2, and the warp carriage 19 swung into an elevated position so as to expose the lower clamps 14 and 15 for the loading of the new warp. Preparatory to this operation, the support 21 for the plush clamp 22 is moved from its lowermost or inactive position into the position shown in Fig. 4 wherein latch member 32 engages with the slot 33. The support is locked in position close to the tying machine by means of the clamping screw 29.

9 The new warp is now placed across the clamps 14 and 15 and the ribbon bar 20a, by unwinding the length L from the clamp B while permitting the clamp C to remain in its position c on the rear side of the loom whip roll. The end of the warp adjacent the clamp B is inserted in the plush clamp 22 and the clamp B allowed to hang suspended in the position b¹.

10 The operator now releases the support 21 from its rockshaft 24 by loosening the screw clamp 29, and swings the support forwardly so as to place the threads of the warp under uniform tension. Thereupon insertion bar 14a is laid upon the warp adjacent the loom side clamp 14 and then moved downwardly and inserted into the notches 45 of the arms 42, 43 and 44 of the carrier 39. It will be observed that in this act, the warp threads are bent downwardly around the rear side of the clamp 14 as shown in broken lines in Fig. 4. To provide sufficient slack for such movement of the insertion bar into the carrier 39, the operator, standing in front of the machine (to the left in Fig. 4), presses his body against the upper end of the support 21 so as to swing the clamp 22 rearwardly the required distance.

11 The next step in the operation is to transfer the insertion bar 14a to the loomside clamp 14 and thus secure the warp threads therein. To do this, the operator depresses the treadle 54 so as to impart a swinging motion to the carrier 39 forcing the insertion bar together with the warp threads into the clamp 14. Upon release of the treadle, the carrier 39 moves reversely, the insertion bar becoming disengaged from its ball detents 47.

12 The operator now adjusts the plush clamp 22 lengthwise of the support 21 so as to correct the angular position of the warp threads relative to the tying mechanism.

13 The new warp is now ready to be secured to

the front clamp 15. Accordingly, the operator places an insertion bar on the top of the warp adjacent the clamp 15 and then forces the insertion bar downwardly and forwardly, bending the warp threads around the rear edges of the bar while carrying the latter into the notches 45 of the several arms of the carrier 40. As before, the operator provides the necessary slack in the threads by pressing with his body on the upper end of the support 21. The insertion bar is then transferred to the clamp 15 by swinging the carrier 40 manually into the dotted line position shown in Fig. 4. It will of course be understood that after the insertion bars have been inserted in their respective clamps, they are locked therein in the conventional manner through the operation of hand levers 185 (Fig. 1). After the clamping operation, the carrier 40 may be returned to its full line position (Fig. 4), determined by the latch member 54b.

The new warp is now sheared between the clamp 15 and the plush clamp 22, preferably adjacent the clamp 15, and the waste ends removed from the clamp 22.

The new warp having thus been "loaded" into the machine, the next operation concerns the loading of the old warp. In doing so, the operator first shifts the frame 25 upwardly (Fig. 7) until the latch 32 engages with the slot 34 in the plate 35 and at the same time swings the clamp support 21 rearwardly close to the frame of the tying machine, locking it in position by actuation of the screw clamp 29.

The insertion bar 16a is placed in the upper notches 46 of the holder 39, and the insertion bar 17a laid on the lower member of the clamp 22. The old warp is now unwound from clamp A and drawn across beneath the clamps 16a and 17a and the ribbon bar 20. As before, the end of the warp is secured in position in the clamp 22 and the clamp A allowed to remain suspended from the warp, whereupon the members of the clamp 22 are secured together by means of the spring clips 22a. The support 21 is now released and swung outwardly to place the old warp under tension and the clamp 22 adjusted longitudinally of the support to correct for any improper angular relationship of the warp threads to the tying mechanism.

The warp carriage 19 is now lowered and latched in position on the tying machine so as to locate the clamps 16 and 17 in opposed relation to the lower clamps 14 and 15. Thereupon, treadle 54 is operated to swing insertion bar carrier 39 forwardly to effect the transfer of insertion bar 16a from the carrier to clamp 16 and thereby secure the warp threads in the clamp.

Insertion bar 17a is now removed from the clamp 22 and inserted in the upper notches 46 of the carrier 40, the bar having been first placed beneath the warp adjacent the clamp 17 so as to press the warp threads upwardly against the clamp. The carrier 40 is now swung rearwardly to transfer the insertion bar 17a into the clamp 17, carrying the warp threads with it and securing the latter to the clamp.

Finally, the upper warp is sheared adjacent the clamp 17, the waste ends removed from the clamp 22 and the support 21 lowered by disengaging the latch 32 from its notch 34 in the plate 33. As the frame together with the support 21 approaches its lowermost or inactive position, the lower end portions 30 of the arms 23 engage with the cams 31 to swing the support close to the frame. The holder 40 may be swung downwardly

alongside the machine frame by releasing the latch member 54b.

When the machine is not in use, the holder 39 may be secured in a position against the loom side thereof. For this purpose, I provide a sliding latch member 56 (Fig. 1) movable into engagement with the treadle 54 so as to hold it in its lowermost position.

It will be seen that by the construction and arrangement provided the operation of loading the old and new warps in the tying machine is greatly facilitated. At the same time the threads of the two warps are maintained in parallel relationship and under uniform tension so as to insure proper operation of the tying mechanism.

I claim as my invention:

1. In a warp tying machine having a main supporting frame, means mounted on said frame for supporting two warps to be united comprising two vertically spaced loom side clamps and two vertically spaced front clamps, each of said clamps comprising an outwardly facing U-shaped member adapted to receive an insertion bar for clamping a sheet of warp threads, a support for an auxiliary thread holder mounted on the front side of the frame and shiftable into either of two positions adjacent the respective front clamps, said support being swingable forwardly in either of said positions to carry said thread holder in a direction away from the frame whereby to place the warp threads under tension, and a pair of insertion bar carriers swingably mounted on the front and loom sides respectively of the frame and each comprising a plurality of arms having notches spaced apart according to the spacing of the opposed clamps and adapted for the reception of insertion bars, said carriers being swingable to transfer insertion bars mounted in said notches to the respective clamps to secure the warp threads therein.

2. In a warp tying machine having a main supporting frame, means mounted on said frame for supporting two warps to be united comprising two vertically spaced loom side clamps and two vertically spaced front clamps, each of said clamps comprising an outwardly facing U-shaped member adapted to receive an insertion bar for clamping a sheet of warp threads, a support for an auxiliary thread holder mounted on the front side of the frame and shiftable into either of two positions adjacent the respective front clamps, said support being swingable forwardly in either of said positions to carry said thread holder in a direction away from the frame whereby to place the warp threads under tension, a pair of insertion bar carriers swingably mounted on the front and loom sides respectively of the frame and each comprising a plurality of arms having notches spaced apart according to the spacing of the opposed clamps and adapted for the reception of insertion bars, said carriers being swingable to transfer insertion bars mounted in said notches to the respective clamps to secure the warp threads therein, and treadle-operated means for swinging the loom side carrier.

3. In a warp tying machine having a main supporting frame, means mounted on said frame for supporting two warps to be united comprising two vertically spaced loom side clamps and two vertically spaced front clamps adapted to receive an insertion bar for clamping a sheet of warp threads, a support for an auxiliary thread holder swingably mounted on the front side of said frame and shiftable into either of two positions so as to support either of said two warps

adjacent their respective clamps, and insertion bar carriers on the front and loom sides of the frame operative to receive insertion bars in either of two positions spaced apart according to the spacing of the opposed warp clamps, and each carrier being movable to carry a bar together with the threads of a warp bearing thereon into one or the other of the two clamps.

4. In a warp tying machine having a main supporting frame, means mounted on said frame for supporting two warps to be united comprising two vertically spaced loom side clamps and two vertically spaced front clamps adapted to receive an insertion bar for clamping a sheet of warp threads, a swinging support for an auxiliary thread holder mounted on the front side of said frame and shiftable into either of two positions so as to support either of said two warps adjacent their respective clamps, insertion bar carriers on the front and loom sides of the frame operative to receive insertion bars in either of two positions spaced apart according to the spacing of the opposed warp clamps and movable to carry said bars together with the threads of warps bearing thereon into the respective clamps, and treadle operated means on said frame for actuating the loom side carrier.

5. In a warp tying machine having a main supporting frame and a pair of vertically spaced clamps each adapted to receive an insertion bar for clamping a sheet of warp threads, and an insertion bar carrier mounted on said frame and operative to support insertion bars in either of two positions spaced apart according to the spacing of said clamps, said carriers being movable to carry said bars together with the threads of the warps bearing thereon into the respective clamps.

6. In a warp tying machine having a main supporting frame and a pair of vertically spaced clamps each adapted to receive an insertion bar for clamping a sheet of warp threads, an insertion bar carrier mounted on said frame and operative to support insertion bars in either of two positions spaced apart according to the spacing of said clamps, said carriers being movable to carry said bars together with the threads of the warps bearing thereon into the respective clamps, and treadle-operated means for actuating said carrier.

7. In a warp tying machine having a main supporting frame, a clamp mounted on said frame and adapted to receive an insertion bar for clamping a sheet of warp threads, and an insertion bar carrier swingably mounted on the frame and operative to receive and support an insertion bar, said carrier being operative in its swinging movement to transfer an insertion bar to the clamp to clamp a sheet of warp threads therein.

8. In a warp tying machine having a main supporting frame, a clamp mounted on said frame and adapted to receive an insertion bar for clamping a sheet of warp threads, and an insertion bar carrier swingably mounted on the frame and operative to transfer an insertion bar thereon to the clamp to clamp a sheet of warp threads therein, said carrier comprising a rockshaft and

5 a plurality of arms mounted on said shaft and including two end arms and a relatively thin intermediate arm dimensioned to pass between the threads of the warp.

9. In a warp tying machine having a main supporting frame, a pair of vertically spaced front clamps each adapted to receive an insertion bar for clamping a sheet of warp threads, a support for an auxiliary thread holder swingably mounted on the front side of said frame and shiftable into either of two vertically spaced positions so as to support either of two warps adjacent their respective clamps, and an insertion bar carrier on the front of the frame constructed to support a pair of insertion bars in either of two positions according to the spacing of said clamps and movable to carry said bars together with the threads of a warp bearing thereon into one or the other of the two clamps.

10. In a warp tying machine having a main supporting frame, a pair of warp clamps mounted on said frame in laterally spaced relation and each adapted to receive an insertion bar to clamp a warp extending across the two clamps and bent around the outer sides of the clamps, a friction clamp support mounted at one side of said frame for movement away from the frame to tension the threads yieldably gripped by the friction clamp, a pair of insertion bar carriers mounted on opposite sides of the frame and movable toward and from the respective warp clamps, each of said carriers being adapted to receive and support an insertion bar in vertically offset relation to the respective clamps whereby when a warp is interposed between the clamps and the respective insertion bars, movement of said carriers toward the clamps will carry the insertion bars together with warps into the clamps.

11. A portable warp tying machine comprising a frame mounted for movement into position adjacent a loom having a loom beam thereon, said frame having stationarily mounted thereon a pair of clamps providing laterally spaced supporting surfaces for a sheet of warp threads extending to the loom beam, an arm yieldably mounted on said frame and adapted to support a plush clamp for clamping the end of the warp and maintaining the same under tension, and an insertion bar carrier movably mounted on said frame and adapted to receive an insertion bar and to support the latter in vertically offset relation to the supporting surface of one of said clamps, said carrier being operable to carry the insertion bar into the adjacent clamp and to clamp therein in warp threads bent around the clamp.

CHARLES B. CRANDALL.
